LENS POLISHING OVERLAY

William C. Seifert, Narbeth, Pa., assignor to Donald W. Kent, Philadelphia, Pa.

Application September 4, 1953, Serial No. 378,527

1 Claim. (Cl. 51—195)

This invention is a new and useful overlay for and method of grinding glass blanks, for example lens blanks, for the production of optical lenses. The invention will be fully understood from the following description read in conjunction with the drawings in which:

Fig. 1 is an exploded perspective view of an overlay to be used in applying the invention;

Fig. 2 is a top view on an enlarged scale of the top layer shown in Fig. 1;

Fig. 3 is a section taken on line 3—3 of Fig. 2;

Fig. 4 is a vertical section through the apparatus in which the grinding and/or polishing may be carried out; and

Fig. 5 is a plan view of one element of the showing in Fig. 4.

Referring to Fig. 1, the elements in composite tape 1 which constitutes the overlay are as follows:

Separating layer 2 is a ribbon of non-adhesive or only slightly adhesive material designed to permit the overlay 1 to be assembled in layers or wound upon itself, but still readily separable as parts of it are required for use. Separating layer 2 may be paper impregnated with a high M. P. wax or may be a thin sheet of poly-per-fluor-ethylene or any other suitable material which is easily separable, i. e. either non-adhesive or only slightly adhesive. Layer 3 is a ribbon (for example, thin cloth) coated on both sides with a suitable adhesive to enable it to adhere firmly to any metal surface against which it may be pressed. Such adhesives are known in the art and, therefore, need not be more fully discussed. Layer 4 is of optical pitch such as wood resin, bees' wax or some other thermoplastic material preferably with a softening point below 100° C. Materials with suitable characteristics are recognized in the art under the general designation of optical pitch. This layer is preferably formed by pouring the material in molten condition onto the ribbon 3 while in level position and then permitting the pitch to cool and freeze in layer form. The margins of the pitch can be fixed by mold boards. Alternatively, the overlay may be initially formed in sheets and slit in ribbon (tape) form after completion. The layer of optical pitch preferably is several times the thickness of adhesive layer 3 and may conveniently be from $\frac{1}{16}$ to $\frac{3}{16}$ of an inch. Layer 5 is a ribbon preferably of thin sheet fibrous felted material with a crinkled surface. The surface ridges are preferably of the order of about $\frac{1}{32}$ of an inch apart and a few thousandths of an inch above the valleys. A sulfite pulp paper "doctored" to develop a crinkled surface such as paper towel stock has been found satisfactory. This material is impregnated with a water insoluble plastic material such as a polymerized unsaturated high molecular weight hydrocarbon. Examples of such hydrocarbons are polythene, poly-per-fluor-ethylene, polybutylene and polyvinyl chloride. The impregnating material must not fill the valleys and destroy the aforementioned relief characteristics. Although these impregnants are normally non-adhesive, they are laid down on layer 4 while the optical pitch is still in molten condition and so develop a strong adhesion to the optical pitch.

An overlay of the material described is preeminently

2

suited to polishing. If grinding is desired, element 5 may be of metal foil and preferably a metal foil consisting predominantly of nickel as more specifically disclosed in my co-pending application Serial No. 378,526.

5 Overlay 1 is assembled for convenience into bundles of flat strips or, alternatively, may be wound in rolls while the pitch is thermoplastic.

The method of use will be evident from the showing in Figs. 4 and 5. Referring to Fig. 5, separating layer 2 is first removed and the remainder, consisting of layers 3, 10 4 and 5, is heated lightly, for example by sweeping over it several times a small flame such as that provided by a Bunsen burner. This heating is continued to a point at which the pitch is just thermoplastic. At this point, a series of strips 6 of the overlay are (Fig. 5) applied to spherical or aspherical surface 7 of the supporting form 8 defining the desired surface to which the blank is to be finished and pressed against this surface to cause adhesive layer 3 to attach itself firmly to this surface. The ends are then trimmed roughly to the margin of surface 7, as indicated in Fig. 5. The lens blank is secured to holder 10 by pitch 11 or in any other suitable way. The glass blank or a master curve is pressed against strips 6 while the pitch is still thermoplastic thereby causing the exposed 15 surface of the strips to conform to the surface of the glass blank or master curve.

20 As soon as the optical pitch in strips 6 has hardened, the overlay is ready for use. If the glass blank is to be ground, the strips faced with metal foil are used and a slurry of an abrasive material is fed continuously or intermittently to the grinding surface while the lens blank 9 is worked against the surface of the strips. The strips will survive a large number of grindings and after they have become worn or should be removed for any other 25 reason, they are easily detached manually.

If the glass blank 9 is to be polished, the strips 6 will be those provided with a face of impregnated, fibrous material defining a crinkled surface as hereinabove described. In this case, an aqueous suspension of rouge will be fed 30 either continuously or intermittently to the polishing surface while the previously ground glass blank is being worked against the polishing surface.

This method of polishing has been tested against the 35 various accepted methods of polishing to finish optical lenses and found to produce a perfect finish in approximately one fourth of the time required by the methods now in use and with a higher degree of uniformity.

40 Surfaces such as those formed by ribbon 5, whether of metal foil to retain abrasive, or of impregnated fibrous material to cause the rouge to exert its polishing effect, will be generically designated as charging surfaces.

I claim:

An overlay for glass polishing in the form of a composite tape including a ribbon of adhesive material, a ribbon of thermoplastic optical pitch of at least $\frac{1}{16}$ " in 45 thickness adhering to said ribbon of adhesive material, a ribbon of rouge retaining material carried by and adhering to said ribbon of optical pitch, said rouge retaining material consisting of paper defining a crinkled surface and impregnated with a water insoluble plastic material 50 while retaining the elevations and depressions of said crinkled surface.
